SANDING BLOCK

Carl W. Reichel, Sacramento, Calif.

Application August 10, 1939, Serial No. 289,342

1 Claim. (Cl. 51—187)

This invention relates to hand tools for gripping or holding abrasive-coated sheets used in polishing or surfacing work.

It is an object of the invention to provide a sanding block particularly adapted to the finishing of the painted surfaces of automobiles or the like.

Another object of the invention is to provide a sanding block which will produce an abraded surface that is perfectly smooth and free of undercutts.

The invention possesses other objects and features of advantage, some of which, together with the foregoing, will be specifically set forth in the detailed description hereunto annexed. It is to be understood that the invention is not to be limited to the specific form thereof herein shown and described as various other embodiments may be employed within the scope of the appended claim.

Referring to the drawing:

Figure 1 is a top plan view of the sanding block of my invention.

Figure 2 is a longitudinal vertical sectional view of the sanding block. The plane in which the view is taken is indicated by the line 2—2 of Figure 1.

Figure 3 is an end elevational view of the sanding block.

Figure 4 is a view showing the action of a sheet of abrasive paper held in the sanding block of my invention.

Figure 5 is a fragmental vertical sectional view showing a modified form of my invention.

In the refinishing and painting of automobile bodies and fenders, the prime requisite of a satisfactory and acceptable job is that the surface to be painted should be absolutely smooth. If there are any slight hollows or raised areas on the surface, regardless of how many coats of lacquer or paint are sprayed on the surface, the imperfections will not be obliterated. It is the usual practice in repainting a body to first level off the body surface by over-filling any areas of the body that may have been denuded of paint with an undercoating material and then smoothing down these filled areas to the level of the surrounding original paint. This last step requires the use of a sanding block surfaced with a suitable abrasive paper, the most common of these blocks being constructed of rubber. In Figure 4, I have shown a section 6 of an automobile body covered by an original paint layer 7 and with two adjoining raised filler coats 8 which occupy areas of the body from which the original paint had

been removed or which may be additional paint coatings applied to the body such as advertising lettering. It will be seen that when a rubber sanding block is passed across the painted surface, the abrasive paper will be forced, by flexing of the block under pressure of the workman's hand, down into the depressions between the filler coats 8 thus abrading the original paint 7, which should not be touched by the abrasive paper until the surface to be painted is almost completely smooth and level, and also feather-edging the edges of the filler coats 8 leaving the center portions of the latter considerably elevated above the level of the original paint 7. This produces a wavy surface and, when once waved, the surface may not be levelled regardless of how long the sanding is continued, all because the flexible rubber sanding block will follow the hills and hollows and will not cut down the high spots. If a surface prepared in this manner is spray painted the resulting high gloss finish will accentuate the unevenness of the surface by reflecting the highlights and shadows of the hills and hollows. I have provided an improved sanding block which overcomes these difficulties.

In detail, the block comprises a unit piece of sheet metal formed to provide a flat base 12 having relatively narrow upwardly rising flanges 13 at each end thereof and taller flanges 14 rising vertically from the sides thereof. The adjoining vertical edges of the side and end flanges are suitably joined together by welding or brazing or the entire base including the flanges may be stamp-drawn from a single piece of material. The upper edge 16 of each side flange 14 is arcuately curved and a curved plate 17 is welded, or otherwise secured along its side edges, to the side flanges. This plate has its opposite ends terminating short of the end flanges 13 to form a pair of rectangular openings 18 at the respective ends of the sanding block. When a sheet of abrasive paper is placed on the outer surface of the base 12 the extending ends of the paper may be folded upwardly over the end flanges 13 and stuffed into the openings 18 so as to attach the paper to the sanding block. The extending side portions of the paper are folded against the sides of the flanges 14, the latter being provided with finger recesses 19 into which the paper may be pressed by the fingers of the operator so as to simultaneously provide for holding the paper on the block and to act as a hand grip.

The bottom surface of the base 12 is provided with a coating of babbitt or other semi-soft metal 21. This coating of metal, softer than that from

which the body of the sanding block is constructed, provides a more desirable backing for the abrasive paper and also, in the event that it becomes nicked and raised in areas due to accident or rough handling, may, by a few strokes over a piece of abrasive paper layed on a flat surface, be quickly restored to its original flat condition.

As shown in Figure 4, when the sanding operation is performed with the sanding block of my invention, the abrasive paper 22 is held absolutely flat because of the inflexibility of the block thus enabling the operator to quickly level off the protruding surfaces of the filler coatings 8 and to render the surface to be painted free of hills and hollows. Since it is possible, with the sanding block of my invention to more rapidly and satisfactorily level off the surfaces to be painted, the time required for preparing the surfaces, over that required when the rubber sanding block is used, is considerably lessened thereby resulting in a material speeding up of production, greater profit per job, and a greater assurance, since the work is more perfect, of the customer being entirely satisfied with the paint job.

In Figure 5 I have shown a modified form of sanding block comprising a hollow sheet metal body 23, shaped similarly to the block previously described, to all outer surfaces of which is banded a relatively thin layer of semi-hard rubber 24.

This rubber layer, backed by the sheet metal body 23, will not flex as does the conventional softer rubber block 9, protects the block against denting should it be accidentally dropped, and frictionally grips the abrasive paper so that the latter is not likely to wrinkle or roll up during the progress of a sanding operation.

Having thus described my invention, what I claim as new and desire to secure by Letters Patent is:

A sanding block to which a sheet of abrasive-coated sheet material may be attached comprising a flat sheet metal base having integral side and end flanges rising from the edges thereof, said side flanges being comparatively longer than said end flanges and being each provided with an arcuate upper edge, an arcuately curved plate secured along opposite edges to the curved upper edges of said side flanges, said plate terminating at its ends in spaced relation to said end flanges to provide between each end of the plate and an end flange an opening into which extending ends of said sheet material placed against said base may be stuffed so as to secure said sheet material to said base, said base having thereon a layer of metal softer than the metal from which said base is constructed, and said side flanges each having therein a depressed portion to provide a finger grip.

CARL W. REICHEL. 30
